VINCENZO MASSACESE, OF NEW YORK, N. Y., ASSIGNOR TO THE MANHATTAN SPRING BED COMPANY, OF NEW YORK, N. Y., A CORPORATION OF NEW YORK

BRACE FOR SPRING STRUCTURES

Application filed December 22, 1926. Serial No. 156,452.

This invention relates to furniture spring structures and has particular reference to an improved resilient bracing means for the upper side edges of bed springs or similar spring structures to prevent a sagging due to the fact that it is a common practice to sit upon the side edges of a bed.

It is appreciated that means for this purpose have been devised but such means are open to a number of objections, namely, that said devices are arranged on opposite sides of the spring and are independent of each other whereby in event of a localized weight being brought to bear on directly opposed points the devices are bent, distorted, or possibly broken, and such devices further include a fixed point or fulcrum for the brace levers or arms resulting in squeaking, and in some instances resulting in rusting of the pivot or fulcrum. To overcome this and other objectionable features and disadvantages, the present invention comprehends a bracing means of the character set forth which includes a floating fulcrum for the brace levers or arms and a resilient connection between each directly opposed pair of said levers or arms, which construction in addition to materially adding to the general efficiency, positively precludes distortion or breakage of the levers or squeaking of the spring when the bed is in use.

The invention furthermore comprehends a brace of the character set forth which is comparatively simple in its construction, inexpensive to manufacture, and install, and which is highly efficient in its purpose.

With the above recited and other objects in view, reference is had to the following specification and accompanying drawings in which there is exhibited one example or embodiment of the invention which is in no way intended as a limitation upon the scope of the appended claims as it is to be clearly understood that variations and modifications which

properly fall within the scope of said claims may be resorted to when found expedient.

In the drawings—

Fig. 1 is a side view of a spring equipped with a bracing means constructed in accordance with the invention;

Fig. 2 is a transverse sectional view therethrough taken approximately on the line 2—2 of Fig. 1, with the helical springs omitted;

Fig. 3 is a fragmentary detail perspective view on an enlarged scale of the bed spring equipped with the bracing means;

Fig. 4 is an enlarged detail sectional view similar to Fig. 2, showing one side of the bracing means and spring;

Fig. 5 is a fragmentary collective perspective view on an enlarged scale illustrating the connection between the brace arm or lever and the reinforcing member of the spring structure.

Referring to the drawings by characters of reference which particularly illustrate the invention as applied to a bed spring, A—A designate the side bars of the main supporting frame of the spring structure; B a superposed reinforcing member, and C the usual conical or spiral springs which are supported by the cross bars D and to which superposed reinforcing member B the marginal springs C have their upper convolutions attached as at E.

In order to provide means for resiliently bracing the reinforcing members B to tension the same against downward movement, and, at the same time, to return said reinforcing members to their normal elevated position, a pair of arms 10—10 are swingingly carried or fulcrumed at 11 to directly opposed points of the reinforcing members B of the opposite sides of the spring structure. The lower ends or terminals 12 of each pair of arms or levers 10 are resiliently connected to each other by spring sections 13—13, one terminal 14 of each of which is attached to a transverse link rod 15 and the opposite

terminal 16 of each of which is engaged in an aperture 17 in the end 12 of the respective lever or arm 10. The end or terminal 12 of each arm 10 is further connected by a coiled contractile spring section 18 to the side bar or rail A. In this manner a floating fulcrum for each arm or lever 10 is provided in lieu of a fixed fulcrum, and it is obvious that the springs 13 and 18 combine, respectively, to 5 resist the downward movement of the reinforced members B when weight is imposed on the upper side edges of the spring structure, while when the weight is removed said springs act to return and maintain the reinforcing members B in their normal position. 10

As will be observed in Figure 4 the inner spring 13, of each pair of the springs 13-18, has its outer end connected to the adjacent end of an arm or lever 10 at a point slightly 20 out of line with and above that of the inner end of an outer spring 18, so that a somewhat continued tensioning effort on the arm or lever 10 in an upward direction will obtain, with the result that a much stronger resistance is offered to any downward movement 25 of the latter under the weight of a person seated on the edge portion of the bed spring than would otherwise be the case. Also, by having these connected spring ends so arranged, the tensioning and resisting efforts 30 thereof are brought immediately into play upon the relieving of the bed spring of the weight of the body or the imposing of the weight of a body thereon.

35 In order to simplify the connection of the arms 10 with the members B, the upper ends thereof are provided with parallel slits defining a plurality of bendable terminals 19 which are bent to embracing engagement about the reinforcing members.

40 It will be observed from this structure that even in event of the imposition of weight on the opposite upper edges of the spring structure at directly opposed points, the device will function in its usual capacity. It 45 will, however, be noted that no rigid pivot is provided which will cause squeaking or which will tend to rust.

It is obvious that as many pairs of arms 50 or levers 10 with their connections may be employed as necessary to support the spring structure edges and the number may be varied according to the size of the spring to which it is applied.

55 What is claimed is:

1. In a furniture spring structure, the combination with a supporting frame including parallel side bars and spaced transverse bars extending between and connecting 60 said side bars, of spiral springs rising from said transverse bars, resilient means interconnecting said spiral springs at the upper ends thereof, a marginal reinforcing element extending about the outer side of the upper 65 ends of the outer of said spiral springs, at-

taching means between said reinforcing element and the adjacent of the said spiral springs, vertically rockable arms secured at their upper ends to said reinforcing element and in spaced relation along the opposite side portions thereof and declining inwardly of the frame to points in the plane of the latter, pairs of opposed spring members transversely alined between the same side bars of the frame and having the adjacent of their ends directly attached to the lower ends of each of said arms one substantially in line with the other, the outer of each pair of spring members having their outer ends attached directly to said side bars, and means connecting the opposed ends of the inwardly disposed of each pair of said spring members. 70 75 80

2. In a furniture spring structure, the combination with a supporting frame including parallel side bars and spaced transverse bars extending between and connecting said side bars, of spiral springs rising from said transverse bars, resilient means interconnecting said spiral springs at the upper ends thereof, a marginal reinforcing element extending about the upper ends of the outer of said spiral springs, attaching means between the said reinforcing element and the adjacent of the said spiral springs, vertically rockable arms secured at their upper ends to said reinforcing element at opposite sides of said frame and declining inwardly of the latter to points substantially in the plane thereof, pairs of opposed spring members extending in transverse alinement between the said side bars of the frame and having the adjacent of their ends directly attached to the lower ends of said arms, the outer ends of the inner of each pair of said spring members being connected to said arms in a plane slightly above the points of connection of the inner ends of the outer of said springs therewith, the outer of each pair of said spring members having their outer ends attached directly to said side bars, and means connecting the opposed ends of the inwardly disposed of each pair of said spring members. 90 95 100

3. In a furniture spring structure, the combination with a supporting frame including parallel side bars and spaced transverse bars extending between and connecting said side bars, of spiral springs rising from said transverse bars in parallel rows, cross connected resilient means interconnecting said spiral springs at the upper ends thereof, a marginal reinforcing element extending about the upper sides of the outer of said spiral springs, attaching means between the said reinforcing element and the adjacent of said spiral springs, pairs of vertically rockable arms disposed in line transversely of said frame and secured at their upper ends to said reinforcing element and declining inwardly of the frame to points substantially 11 12 13 14 15 16 17

in the plane of the latter, pairs of opposed
5 spring members extending in line transverse-
ly between the said side bars of the frame and
having the adjacent of their ends directly
10 attached to the lower ends of said arms, the
outer ends of the inner of said spring mem-
bers slightly out of line with respect to the
inner ends of the outer of said spring mem-
bers, the outer of each pair of said spring
15 members having their outer ends attached
directly to said side bars, and means connect-
ing the opposed ends of the inwardly dis-
posed of each pair of said spring means.
